United States Patent Office

Des. 181,153
Patented Oct. 8, 1957

181,153

ILLUMINABLE ADVERTISING DISPLAY

Buford M. King, Jr., Northbrook, Ill., assignor to Carling
Brewing Company, a corporation of Virginia

Application June 18, 1956, Serial No. 41,959

Term of patent 14 years

(Cl. D1—12)

Fig. 1.

Fig. 2.

Fig. 1 is a front elevational view of an illuminable advertising display, showing my new design.

Fig. 2 is a side elevational view thereof.

The essential features of the design reside in the portions which are shown in full lines in the drawings.

I claim:

The ornamental design for an illuminable advertising display, as shown and described.
